UNITED STATES PATENT OFFICE.

HARRISON GASTON BREWER, OF WASHINGTON, DISTRICT OF COLUMBIA.

DESIGN FOR A BADGE.

SPECIFICATION forming part of Design No. 31,059, dated June 27, 1899.

Application filed May 22, 1899. Serial No. 717,857. Term of patent 31 years.

To all whom it may concern:

Be it known that I, HARRISON GASTON BREWER, a citizen of the United States, residing at No. 2008 F street northwest, in the city of Washington, District of Columbia, have invented and produced a new and original Design for a Badge, of which the following is a specification, reference being had to the accompanying drawing, forming part thereof.

10 The figure represents the design in plan. As shown in the drawing, the leading or material features of my design consist of several figures upon a circular base, comprising the unitary design shown. The figure on the

15 left represents President McKinley in a sitting position, contemplating a map representing the Atlantic and Pacific oceans and the connecting-link—the Nicaragua canal. The

figure in the center represents Liberty holding the United States flag. The figure on the right represents Justice holding the scales in one hand and the scroll in the other. The rays of the sun are represented on right and left in the design.

It is apparent that this design is applicable for many decorative purposes.

Having described my invention, what I claim as new, and desire to secure by Letters Patent, is—

The design for a badge, substantially as herein shown and described.

HARRISON GASTON BREWER.
